UNITED STATES PATENT OFFICE.

JACOB HERBERT, OF DETROIT, MICHIGAN.

PORTRAIT FINGER-RING.

1,334,859.

Specification of Letters Patent. Patented Mar. 23, 1920.

Application filed November 1, 1918, Serial No. 260,682. Renewed September 27, 1919. Serial No. 326,936.

To all whom it may concern:

Be it known that I, JACOB HERBERT, a citizen of the United States, and a resident of Detroit, in the county of Wayne and State of Michigan, have invented a new and Improved Portrait Finger-Ring, of which the following is a full, clear, and exact description.

The object of the invention is to provide a new and improved portrait finger ring arranged to provide a convenient means for holding a portrait, to allow of viewing the portrait from the outside, and to permit of replacing the portrait by another whenever it is desired to do so. Another object is to make the holding means for the portrait an ornamental feature of the finger ring thus enhancing the appearance of the ring.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a perspective view of the portrait finger ring with the cover of the portrait holder in open position;

Fig. 2 is an enlarged sectional side elevation of the finger ring with part of the annular band shown in elevation; and

Fig. 3 is a cross section of the same.

The plain annular band 10 of the portrait finger ring is provided with a thickened and wider top portion 11 provided in its outer face with a depression or recess 12 adapted to contain a portrait 13. This portrait is usually provided with a cardboard body and rests on an annular seat 14 formed by the upwardly and outwardly inclined lower portions of the sides of the thickened portion 11, as plainly indicated in Figs. 2 and 3. The recess 12 is adapted to be closed by a cover 15 provided with a depending annular flange 17 snugly fitting against the inner face of

the wall 16 of the top portion 11 so as to normally hold the cover 15 in closed position by frictional contact of the flange 17 with the side wall 16 of the thickened portion 11. The lower edge of the annular flange 17 is

adapted to rest on the top marginal portion 55 of the portrait 13 so as to securely hold the latter in position on its seat 14 and thus prevent the portrait from shifting. The cover 15 is provided with an opening 19 in the 60 wall of which is set an ornament 20 preferably in the form of a precious diaphanous stone, which enhances the appearance of the ring and permits of viewing the portrait 13 from the outside without opening the 65 cover 15.

From the foregoing it will be seen that the wearer or owner of the ring can readily open the cover 15 and remove the portrait 13 and replace it by another whenever it 70 is desired to do so. It will also be noticed that the portrait shows through the diaphanous ornament 20 to enhance the appearance of the ring.

Having thus described my invention, I 75 claim as new and desire to secure by Letters Patent:—

1. A portrait finger ring comprising a band having a thickened and widened top portion provided in its outer face with a 80 recess adapted to receive a portrait, and a hinged cover closing the recess and having a depending annular flange fitting the inner faces of the walls of the recess to hold the cover closed by frictional contact and 85 for engaging the portrait in the recess to prevent it from shifting, said cover having a diaphanous stone ornament to permit of viewing the portrait.

2. A portrait finger ring comprising an 90 annular band having a thickened and widened top portion provided in its outer face with a recess adapted to receive a portrait, the lower portions of the side walls of the said top portion being beveled upwardly 95 and outwardly to form an annular seat below its upper edge, and a hinged cover closing the said recess, the said cover having a depending annular flange fitting against the inner faces of the side wall of the said 100 recessed top to hold the cover closed by frictional contact and for engaging the portrait to hold it on the said seat.

3. A portrait finger ring comprising an 105 annular band having a thickened and widened top portion provided in its outer face with a recess, the lower portions of the side walls of the said top portion being beveled upwardly and outwardly to form an

annular seat, said recess being adapted to receive a portrait seated on the said seat, and a hinged cover closing the said recess, the said cover having a depending annular flange 5 fitting against the inner faces of the side wall of the said recessed top to hold the cover closed by frictional contact, the said

flange also serving to hold the said portrait to the seat, the said cover being provided with an opening and with a diaphanous 10 precious stone ornament set in the wall of the said cover opening to permit of viewing the said portrait.

JACOB HERBERT.
